(74) Attorney, Agent, or Firm — Alan D. Kamrath;
Kamrath IP Lawfirm, P.A.(57) **CLAIM**

The ornamental design for a pull rod handle for luggage case, as shown and described.

DESCRIPTION

FIG. 1 is a perspective view of a pull rod handle for a luggage case showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The unshaded surfaces within the circular features on the bottom of the handle in FIG. 7 represent portions of the handle which form no part of the claimed design.
